Patented Mar. 18, 1958

182,340

TIRE

Andrew J. Palko, deceased, late of Akron, Ohio, by
Gladys M. Palko, executrix, Akron, Ohio, assignor to
The Goodyear Tire & Rubber Company, Akron, Ohio,
a corporation of Ohio

Application September 12, 1956, Serial No. 42,913

Term of patent 14 years

(Cl. D90—20)

Fig. 1 is a perspective view of a tire showing the new design, it being understood that the full line portion of the design is repeated throughout the circumference of the tire shown by means of broken lines, the opposite side being substantially the same as that shown;

Fig. 2 is a top plan view of a portion thereof;

Fig. 3 is a fragmentary cross-sectional view, taken on the line 3—3 of Figure 1, and

Fig. 4 is an enlarged fragmentary side view.

What is claimed is:

The ornamental design for a tire, as shown and described.
